CLAIM

The ornamental design for a synthesizer, as shown and described.

DESCRIPTION

FIG. 1 is a perspective view of a synthesizer showing my new design.

FIG. 2 is a top view of the synthesizer of FIG. 1.

FIG. 3 is a bottom view of the synthesizer of FIG. 1.

FIG. 4 is a front elevational view of the synthesizer of FIG. 1.

FIG. 5 is a rear elevational view of the synthesizer of FIG. 1.

FIG. 6 is an enlarged right side elevational view of the synthesizer of FIG. 1.

FIG. 7 is an enlarged left side elevational view of the synthesizer of FIG. 1.

FIG. 8 is a perspective view of the synthesizer of FIG. 1, with elements removed for clarity.

FIG. 9 is a top view of the synthesizer of FIG. 8, with elements removed for clarity.

FIG. 10 is a bottom view of the synthesizer of FIG. 8, with elements removed for clarity.

FIG. 11 is a front elevational view of the synthesizer of FIG. 8, with elements removed for clarity.

FIG. 12 is a rear elevational view of the synthesizer of FIG. 8, with elements removed for clarity.

FIG. 13 is an enlarged right side elevational view of the synthesizer of FIG. 8, with elements removed for clarity.

FIG. 14 is an enlarged left side elevational view of the synthesizer of FIG. 8, with elements removed for clarity.

(Continued)

FIG. 15 is a perspective view of the synthesizer of FIG. 1, with elements removed for clarity.

FIG. 16 is a top view of the synthesizer of FIG. 15, with elements removed for clarity.

FIG. 17 is a bottom view of the synthesizer of FIG. 15, with elements removed for clarity.

FIG. 18 is a front elevational view of the synthesizer of FIG. 15, with elements removed for clarity.

FIG. 19 is a rear elevational view of the synthesizer of FIG. 15, with elements removed for clarity.

FIG. 20 is a right side elevational view of the synthesizer of FIG. 15, with elements removed for clarity; and,

FIG. 21 is a left side elevational view of the synthesizer of FIG. 15, with elements removed for clarity.

The broken line disclosure is understood to be for illustrative purposes only and forms no part of the claimed design.
